LAMP SHADE

Filed Sept. 18, 1929

2 Sheets-Sheet 2

UNITED STATES PATENT OFFICE

HENRY R. DURINICK, OF BROOKLYN, NEW YORK

LAMP SHADE

Application filed September 18, 1929. Serial No. 393,510.

This invention relates broadly to electrical fixtures and has more particular reference to a shade for electric lamps.

The primary object of this invention is therefore the provision of an improved lamp shade for electric lamps in which a pair of frame structures are hingedly connected together for vertical swinging movement whereby the sides of the shade may be adjusted whereby the lamp provided with the shade may be dimmed to any desired extent depending upon circumstances, as for example whether one desires a fairly bright light, such as would be used for reading purposes or the like, or a dim glow as may be desired when the lamp is left burning for dimly illuminating a room or the like.

A still further important object of the invention resides in the provision of a structure of the character above mentioned, having lamp supporting means incorporated therein, together with means for supporting the shade on any suitable support, such as for example the back of a bed.

A still further object of the invention is to provide a pair of hingedly mounted frame structures adapted to form the entire lamp supporting structure, and to be covered with a suitable fabric covering, artistically arranged in conjunction with lamp supporting means for supporting an electric lamp at a hinged part of the shade and entirely within the confine of the fabric covering.

A still further object of the invention is to provide a structure of the character above set forth, which is comparatively simple in construction, consisting of comparatively few parts, may be manufactured and retailed at nominal cost, and which is especially adapted for use as a bed lamp.

Other objects and advantages of the invention, will become apparent during a study of the following description, taken in connection with the accompanying drawings, wherein:

Figure 1 is a perspective view of a lamp shade constructed in accordance with the present invention, the same being shown in a collapsed or closed position;

Figure 2 is a similar view of the shade

showing the same in an extended or opened position,

Figure 3 is a perspective view of the lamp shade frame, the same being shown in a closed position and having the fabric covering removed,

Figure 4 is a front elevational view of one of the front sections,

Figure 5 is a top plan view more fully illustrating the hinge connection between the frame,

Figure 6 is a transverse sectional view taken through the hinge connection,

Figure 7 is a perspective view of a ferrule forming a part of the hinge construction.

With reference more in detail to the drawings, it will be seen that my improved lamp shade comprises a pair of frame sections designated generally by the reference characters 5 and 6 respectively. Each of the frame sections are so constructed as to provide a pair of spaced parallel forward vertical frame members and a pair of spaced bowed rear frame members, which rear frame members are so bowed that when a fabric covering is placed thereon in a manner to be hereinafter more fully set forth, the outer end faces or surfaces presented are somewhat in the nature of eccentric surfaces.

From the foregoing then it will be appreciated that the completed shade as shown to advantage in Figures 1 and 2 is substantially heart shaped, the hinge connection between the frames being at substantially the apex of the heart.

With reference to the structure more in detail, it will be seen that each of the frame sections 5 and 6 respectively are as before intimated substantially identical in construction, and each comprise a pair of inter-connected substantially L-shaped rods preferably wire, and providing a pair of vertical frame members 7 and 8 respectively and top and bottom horizontal frame members 9 and 10 respectively.

The frame members 7 and 9 form one of the L-shaped wire rods, while the frame members 8 and 10 form the other of said L-shaped wire rods. The frame member 7 is of a length greater than the length of the frame member

8, and said frame member 7 at the lower end thereof extends beyond the lower horizontal frame member 10 to provide a finger engaging handle designated as at 11.

5 Similarly, the upper frame member 9 is of a length less than the length of the lower frame member 10, and the frame members 9 and 10 have their ends welded to the adjacent end portions of the frame members 7 and 8. Thus it will be appreciated that the vertical frame members 7 and 8 incline gradually upwardly so that obviously the frame sections 5 and 6 taper toward their upper ends.

15 Wire frame members 12-12 are welded at their upper ends to the L-shaped frame members adjacent the upper horizontal frame bar 9 while at their lower ends said frame members 12 are welded to said L-shaped members adjacent the lower horizontal frame member 10.

The frame members 12 are bowed as at 13-13, the distance between the vertical frame sections 7 and 8 and the corresponding frame members 12-12 being greater adjacent the bottom of the frame sections 5 and 6 than at the top thereof.

20 At their bowed portions, the frame members 12-12 are connected through the medium of a cross frame member 14, the ends of which cross member 14 are welded to the adjacent frame members 12-12. At their upper ends, the frame sections 5 and 6 are hingedly connected together as designated 35 generally at 15.

In forming this hinge connection 15 I provide an elongated sleeve or ferrule 16 loosely mounted on the top frame member 9 of the frame section 5. Next I provide a pair of spaced parallel rods or wires 17 adapted for disposition between the sleeve 16 and the top frame member 9 of the frame section 6, the sleeve 16, wires 17 and the upper frame member 9 of the frame section 6 all welded together to provide a single mass designated generally by the reference character 18 thus forming a strong and durable hinge joint between the frame sections 5 and 6.

40 It is to be understood of course that the sleeve 16 shifts about the horizontal frame member 9 of the frame section 5, rather tightly so as to set up a binding action between the sleeve 16 and member 9, so that 45 when the frame sections 5 and 6 are swung outwardly away from one another or inwardly toward one another, said frame sections will be maintained any predetermined distance apart, thus enabling the lamp shade 50 to be adjusted for assuming any desired size.

Welded to the inner bowed frame members 12 of the respective frame sections, adjacent the upper and lower ends thereof are the elongated shanks 19 of support engaging hooks 20, the hooked end portions of which

extend upwardly beyond the upper hinged portions of the frame sections 5 and 6.

The hooks 20 are adapted to engage any suitable support such as the upper edge of the back of a bed, for supporting the lamp shade thereon.

One of the frame sections, as herein shown, the frame section 6, adjacent its upper hinged end is provided with a lamp supporting member 20, which lamp supporting member 20 is preferably formed of wire and has its terminals welded to the upper end portion of the frame members 12 adjacent the upper frame member 9 of the said frame section.

25 The member 20 intermediate its ends is bent to provide a loop 21 for the reception of a conventional lamp socket, whereby an electric lamp as shown may be supported in a depending position within the frame section 6 and in close proximity to the hinged connection, so that the lamp will be disposed at approximately the apex of the completed substantially heart shaped lamp shade.

In completing the shade, each of the frame sections 5 and 6 has a suitable fabric covering 22, which covering 22 has its longitudinal edges covering the frame members 12-12, and said covering 22 extends from the upper frame member 9 to the lower frame member 10.

30 Likewise the front and rear of the frame sections are provided with a suitable fabric covering 23 which completely conceals and extends between the adjacent frame members 7 and 12 and 8 and 12 respectively.

At the front of the shade, and extending between the frame members 7 of the frame sections 5 and 6 is a substantially V-shaped fabric 24 which is secured at its opposite edges to the frame members of the respective frame sections. The usual pull chain 25 of the electric lamp socket extends downwardly from the shade and at its lower end may be provided with an ornamental finger grip 26.

35 Likewise, the connecting web or fabric 24 between the frame sections on the outer face thereof may have some suitable decoration or ornament 27 arranged thereon.

40 In actual practice, the lamp shade having the electric lamp mounted therein as before described, may be suspended from the top of the back of a bed, the hook 20 engaging the upper edge of the bed so that the lamp shade extends parallel to the back of the bed. Obviously, one by placing his fingers on the extension or hand grip 11-11 may move the frame sections 5 and 6 upon their hinge connection toward or away from one another for increasing or decreasing the size of the lamp.

45 The friction set up between the sleeves or ferrule 16 and the upper frame member 9 to which it is attached, will permit of the section being disposed at any adjusted position relative to one another so that when the sections are swung upon their hinged joints,

any predetermined distance, the sections of the shade will remain fixed in that position thus enabling one to regulate the size of the shade.

5 It is yet to be mentioned, that the fabric coverings 22 and 23 may be so arranged on the respective frame sections, in any suitable and desired manner, to produce an artistic and attractive lamp shade as illustrated in Figures 1 and 2, that is, the fabric may be 10 accordion pleated or otherwise artistically arranged to give a neat and attractive appearance. To provide a finish for the shade, I may utilize a beading 28, which beading 15 28 will follow the frame members of the respective sections, that is, the beading will extend along the vertical frame members 7 and 8, the upper and lower horizontal frame members 9 and 10, and the bowed frame members 20 12, thus adding a more finished appearance to the shade.

However the arrangement of the fabric is not limited to this specific arrangement as herein set forth but obviously may be arranged in any manner as may suit the taste 25 of the individual. Likewise, the hooks 20 are arranged within a covering or sheathing 29 of suitable material, so that when the hooks are engaged over the upper edge of the bed danger of scratching, marring or otherwise disfiguring the bed or furniture to which 30 the shade may be suspended will be eliminated.

It is believed that from the foregoing description, taken in connection with the accompanying drawings, a clear understanding of the construction, utility and advantages 35 of a lamp shade of this character will be had by those skilled in this art.

40 Even though I have herein shown and described the preferred embodiment of my invention, it is to be understood that I do not wish to limit myself to the specific details set forth, but that it is to be understood the invention is susceptible to certain changes, such as in the size, shape, materials used and 45 other similar details as coming within the spirit of the invention as herein described and the scope of the appended claims.

50 Having thus described my invention, what I claim as new is:

1. A lamp shade adapted to be suspended from a suitable support, said shade comprising a pair of hingedly connected sections, 55 each of said sections embodying a skeleton frame, a lamp supporting member arranged in one of said skeleton frame sections, and a fabric covering for the respective frame sections.

60 2. A lamp shade of the character described, and adapted to be mounted on a suitable support, said shade comprising a pair of hingedly connected skeleton frame sections, a covering for each of said sections, means for retaining the frame sections in a predetermined

relative adjusted position, one of said frame sections having a lamp supporting member arranged therein.

3. A lamp shade of the character described, comprising a pair of frame sections, each of 70 said sections comprising a pair of relatively straight frame members, upper and lower cross frame members connecting the first mentioned frame members adjacent the upper and lower ends thereof, bowed frame 75 members secured at their ends to said first mentioned frame members adjacent the upper and lower ends of said first mentioned frame members, a fabric covering for each of said frame sections, said covering 80 concealing the frame members of the respective sections, and a support engaging member carried by each of said frame sections.

4. A lamp shade of the character described, comprising a pair of frame sections, each of 85 said sections comprising a pair of relatively straight frame members, upper and lower cross frame members connecting the first mentioned frame members adjacent the upper and lower ends thereof, bowed frame 90 members secured at their ends to said first mentioned frame members adjacent the upper and lower ends of said first mentioned frame members, a fabric covering for each 95 of said frame sections, said covering concealing the frame members of the respective sections, and a support engaging member carried by each of said frame sections, and one of said frame members having a lamp supporting member arranged therein.

100 5. A lamp shade of the class described, comprising a pair of skeleton frame sections, each of said frame sections comprising a pair of converging relatively straight frame members, upper and lower cross frame members secured at their ends to the first mentioned frame members adjacent the upper and lower ends of said first mentioned frame members, longitudinally bowed frame members secured at their ends to the first mentioned frame members adjacent said cross frame members, said bowed frame members extending and being disposed in longitudinally spaced relation, a strip of fabric extending between said bowed frame members and from said upper cross frame members to said lower cross frame members, strips of fabric arranged between said relatively straight frame members and said longitudinally bowed frame members on each of said skeleton frame sections, a substantially V-shaped strip of fabric secured to and extending between one of the relatively straight frame members of the respective sections and entirely closing the front of the lamp shade, and means for 105 hingedly connecting said sections at their upper cross members, whereby said sections may be swung away from one another for increasing or decreasing the size of the lamp shade.

110 6. A lamp shade of the class described, 115 comprising a pair of skeleton frame sections, each of said frame sections comprising a pair of converging relatively straight frame members, upper and lower cross frame members secured at their ends to the first mentioned frame members adjacent the upper and lower ends of said first mentioned frame members, longitudinally bowed frame members secured at their ends to the first mentioned frame members adjacent said cross frame members, said bowed frame members extending and being disposed in longitudinally spaced relation, a strip of fabric extending between said bowed frame members and from said upper cross frame members to said lower cross frame members, strips of fabric arranged between said relatively straight frame members and said longitudinally bowed frame members on each of said skeleton frame sections, a substantially V-shaped strip of fabric secured to and extending between one of the relatively straight frame members of the respective sections and entirely closing the front of the lamp shade, and means for hingedly connecting said sections at their upper cross members, whereby said sections may be swung away from one another for increasing or decreasing the size of the lamp shade.

120 6. A lamp shade of the class described, 125 comprising a pair of skeleton frame sections, each of said frame sections comprising a pair of converging relatively straight frame members, upper and lower cross frame members secured at their ends to the first mentioned frame members adjacent the upper and lower ends of said first mentioned frame members, longitudinally bowed frame members secured at their ends to the first mentioned frame members adjacent said cross frame members, said bowed frame members extending and being disposed in longitudinally spaced relation, a strip of fabric extending between said bowed frame members and from said upper cross frame members to said lower cross frame members, strips of fabric arranged between said relatively straight frame members and said longitudinally bowed frame members on each of said skeleton frame sections, a substantially V-shaped strip of fabric secured to and extending between one of the relatively straight frame members of the respective sections and entirely closing the front of the lamp shade, and means for hingedly connecting said sections at their upper cross members, whereby said sections may be swung away from one another for increasing or decreasing the size of the lamp shade.

130 6. A lamp shade of the class described, 135 comprising a pair of skeleton frame sections, each of said frame sections comprising a pair of converging relatively straight frame members, upper and lower cross frame members secured at their ends to the first mentioned frame members adjacent the upper and lower ends of said first mentioned frame members, longitudinally bowed frame members secured at their ends to the first mentioned frame members adjacent said cross frame members, said bowed frame members extending and being disposed in longitudinally spaced relation, a strip of fabric extending between said bowed frame members and from said upper cross frame members to said lower cross frame members, strips of fabric arranged between said relatively straight frame members and said longitudinally bowed frame members on each of said skeleton frame sections, a substantially V-shaped strip of fabric secured to and extending between one of the relatively straight frame members of the respective sections and entirely closing the front of the lamp shade, and means for hingedly connecting said sections at their upper cross members, whereby said sections may be swung away from one another for increasing or decreasing the size of the lamp shade.

comprising a pair of skeleton frame sections, each of said frame sections comprising a pair of converging relatively straight frame members, upper and lower cross frame members 5 secured at their ends to the first mentioned frame members adjacent the upper and lower ends of said first mentioned frame members, longitudinally bowed frame members secured at their ends to the first mentioned frame 10 members adjacent said cross frame members, said bowed frame members extending and being disposed in longitudinally spaced relation, a strip of fabric extending between said bowed frame members and from said upper 15 cross frame members to said lower cross frame members, strips of fabric arranged between said relatively straight frame members and said longitudinally bowed frame members on each of said skeleton frame sections, 20 a substantially V-shaped strip of fabric secured to and extending between one of the relatively straight frame members of the respective sections and entirely closing the front of the lamp shade, and means for 25 hingedly connecting said sections at their upper cross members, whereby said sections may be swung away from one another for increasing or decreasing the size of the lamp shade, said last mentioned means comprising 30 a ferrule adapted to receive the upper cross frame member of one of said frame sections for frictional engagement with said cross frame member and means for rigidly securing said ferrule to the upper cross member of 35 the other of said frame sections.

7. A lamp shade comprising a pair of duplicate skeleton frame sections, means for hingedly connecting said frame sections at one end whereby said sections may be swung 40 toward or away from one another to assume a predetermined spaced relation to one another, a fabric covering for each of said sections to provide spaced parallel front and rear walls, and a downwardly inclined side 45 wall merging into a curved bottom wall, a lamp socket engaging and supporting member carried in one of said sections at the top thereof, a support engaging hook carried by each of said sections, and a V-shaped strip 50 of fabric arranged between the frame sections to form a collapsible connecting wall between the front walls of said frame sections.

In testimony whereof I affix my signature.
55 HENRY R. DURINICK.
